UNITED STATES PATENT OFFICE.

DANIEL H. NICKELS, OF CLEVELAND, OHIO, ASSIGNOR OF ONE-TENTH TO GEORGE M. ADAMS, OF CLEVELAND, OHIO.

AUTOMATIC LUBRICATOR.

1,178,937.

Specification of Letters Patent. Patented Apr. 11, 1916.

Application filed August 17, 1914. Serial No. 857,075.

To all whom it may concern:

Be it known that I, DANIEL H. NICKELS, a citizen of the United States, and resident of Cleveland, in the county of Cuyahoga, 5 and State of Ohio, have invented certain new and useful Improvements in Automatic Lubricators, of which I hereby declare the following to be a full, clear, and exact description, such as will enable others 10 skilled in the art to which it appertains to make and use the same.

The objects of the invention are to provide an automatically acting device for supplying lubrication to the journal box of an 15 axle or shaft, and particularly adapted to lubricate the journal box of a railway car axle, so as to prevent overheating the axle when on the road.

Since long distances are traversed by rail- 20 way trains and it is impossible to supply oil to them at sufficiently frequent intervals en route, to prevent overheating a sufficient supply of lubricant must be stored in the journal box to last upon the trip or a large 25 portion thereof, and be automatically applied to the axle and journal. To accomplish this object a journal box having a chamber capable of storing lubricant is provided and means are attached to the 30 axle which by the continuous rotation thereof will automatically and continuously pour the lubricant thereover.

The invention comprises the construction of box and self lubricating axle hereinafter 35 described, shown in the accompanying drawings and specifically pointed out in the claims.

In the accompanying drawings Figure 1 is a longitudinal section of a car axle journal showing the storage reservoir and automatic lubricating device; Fig. 2 is a trans- 40 verse section looking into the box; Fig. 3 is a plan view of the spring which retains the wiper in position; Fig. 4 is an end view of one of the retaining nuts therefor; Figs. 45 5 and 6 are side and plan views respectively of one of the retaining bolts therefor; Fig. 7 is a perspective view of the double cup bearing cross bars.

50 In these views A is the journal box, having a hooded front portion A', in the lower portion of which the lubricant is stored. Transversely attached to the front end of the axle is shown a cross bar B which rotates freely in the hooded portion of the

journal box and in its projecting extremities are formed the cups b, b, which face toward the axle and take up the lubricant and pour it upon the front end of the axle which projects at C and into the trough 60 shaped openings d, d, in the upper face of the bearing D, oil holes d', d' lead from these openings to the axle. The front of the bearing D projects at D' to so position the openings d as to receive freely the lubricant 65 from the cups, from which it is conveyed underneath the bearing D and spread over the axle.

The cups b, b, in each end of the trans- 70 verse bar are preferably two in number and are separated by means of a partition b', so as to act as efficiently as possible in each direction as the axle rotates forward and backward.

A broad annular shoulder E upon which 75 the cups revolve retains the lubricant therein and an inlet opening F is formed therein at the lower end through which the cups receive the lubricant from the body of the journal box and the lubricant is delivered 80 through an opening G at the central point above the axle. This shoulder may be an attached band or ring if desired and of the same or different substance from that of the 85 hood or journal box.

The transverse bar B is preferably se- 90 cured to the outer end of the axle by means of one or more studs H, H, which are pro- vided with square stems inserted through square holes b², b², in the bar B which pre- 95 vents the studs from becoming loosened and a retaining spring B' through which the bolts pass, rests at its ends upon the ends of the bar B and maintains the bar in contact with the shoulder.

The nuts J, J, are preferably provided 100 with side flanges, j, j, which are passed over the sides of the spring and prevent the nuts from becoming loosened. These precautions are necessary on account of the continuous jar to which the axles are subjected.

A trough shaped and inclined member is seen at K which is some what raised above the bottom of the reservoir and which has the effect of preventing the lubricant from 105 running out of the rear end of the journal box when the axle is inclined or when rapidly going around a curve which would have the effect of throwing the lubricant out the rear opening.

Having described the invention what I claim as new and desire to secure by Letters Patent is:

1. In a car axle lubricator, the combination with an axle provided with a pair of bearing pins; of a lubricant transporting bar provided with bearing openings mounted on and traveling upon said bearing pins, a spring provided with openings loosely and movably mounted on said bearing pins and having its ends impinging upon the outer ends of said lubricant transporting bar, and spring retaining members adjustably mounted on said bearing pins whereby the ends of said transporting bar may be independently adjusted.
2. In a car axle lubricator, the combination with an axle provided at its ends with spaced bearing members, and a journal box 20 provided with an axle bearing above said axle and a lubricant reservoir below the latter and also having lubricant ports communicating with said reservoir and said bearing; of a lubricant transporting bar 25 loosely and resiliently mounted on said spaced bearing members and having its ends provided with lubricant carrying receptacles traversing said journal box and adapted to receive lubricant from said reservoir and 30 discharge the same to said bearing member through said lubricant ports, a bow spring provided with openings loosely and movably mounted on said spaced bearing members and having its ends impinging upon 35 the outer ends of said lubricant transporting bar, and spring retaining members adjustably mounted on said spaced bearing members and normally interlocking with said bow spring for independently adjusting the 40 ends of said lubricant transporting bar.
3. In a car axle lubricator, an axle provided at its end with spaced bearing members, a lubricant transporting bar provided with bearing openings loosely receiving and taking over said spaced bearing members, 45 a bow spring provided with openings loosely receiving and taking over said spaced bearing members and having its free ends bearing against the ends of said transporting bar, and spring retaining members 50 adjustably mounted on said bearing members whereby said transporting bar is adapted to ride and travel upon said bearing members and the ends independently adjusted through said adjustably mounted 55 spring retaining members.
4. In combination with an axle, a journal box including an extended front provided with an annular shoulder having lubricant receiving and discharging ports above and below said axle, a transverse bar extending across the front of said axle and rotatable in said extended front, said bar being provided at its ends with oppositely arranged lubricant receiving cups traversing said annular shoulder and receiving and discharging lubricant from and through said ports below and above said axle, respectively, a bow spring for retaining said bar in place, and spaced bar and spring carrying and adjusting members on said axle upon which the intermediate portions of said transverse bar and bow spring are mounted and adjusted.

In testimony whereof, I hereunto set my hand this 8th day of Aug. 1914.

DANIEL H. NICKELS.
